DESIGN FOR A GLOBE FOR A LIGHTING FIXTURE

Albert L. Arenberg, Highland Park, Ill., assignor to Patent License Corporation, Chicago, Ill., a corporation of Illinois

Application April 17, 1939, Serial No. 84,344

Term of patent 14 years

To all whom it may concern:

Be it known that I, Albert L. Arenberg, a citizen of the United States, residing at Highland Park, in the county of Lake and State of Illinois, have invented a new, original, and ornamental Design for a Globe for a Lighting Fixture, of which the following is a specification, reference being had to the accompanying drawing, forming a part thereof.

In the drawing:

Fig. 1 is a face view of the globe, showing my new design;

Fig. 2 is a side view of the globe;

Fig. 3 is an end view of the same; and
Fig. 4 is a transverse section through the globe.

The design is characterized by a light transmitting globe of the contour shown, having the transversely curved rectangular center portion transparent and the marginal sides thereof light diffusing and arranged and disposed in the particular manner illustrated in the drawing.

I claim:

The ornamental design for a globe for a lighting fixture, substantially as shown and described.

ALBERT L. ARENBERG.
